REEL FOR DRYING THREAD OR THE LIKE

Lavern J. Jordan, Fairview Village, Ohio, assignor to Industrial Rayon Corporation, Cleveland, Ohio, a corporation of Delaware

Application March 9, 1937, Serial No. 129,866

6 Claims. (Cl. 34—29)

This invention relates to thread store devices on which filaments, threads, tapes, bands, tubes and similar articles, hereinafter referred to as "thread or the like," may, by the action of the elements of the device, be continuously wound and longitudinally advanced in a plurality of helical or generally helical turns. Among other things, the invention concerns improvements on reels of the type shown, described and claimed in 5 British Patent No. 413,414. Such reels, broadly speaking, comprise two rigid, generally cylindrical members mounted with their axes slightly offset from and inclined to each other, the periphery of each generally cylindrical member comprising a plurality of longitudinally extending bar members 10 alternating with the bar members of the other generally cylindrical member.

The invention relates particularly to thread store devices, specifically reels of the type above described, upon which thread or the like may be dried. It has been found by experiment that the rate of drying of the thread or the like on such a reel is a function of the extent of the contact between the thread or the like and the bar members of the reel. To take advantage of this relationship, the thread-bearing surfaces of the bar members are made of maximum area. By virtue of a high heat capacity of the associated parts, they are maintained as nearly as possible 20 at a constant temperature. In consequence, the thread or the like undergoes substantially uniform drying throughout its entire length. This application is in part a continuation of application Serial No. 61,954, filed February 1, 1936, for "Reel."

While the invention is equally applicable to the drying of thread or the like manufactured by cuprammonium, cellulose acetate, nitrocellulose and other processes, it will be described hereinafter as applied to the drying of multiple filament thread manufactured by the viscose process.

In the drawings, in which are shown two different embodiments of the invention and in which like reference characters refer to like parts throughout, Figure 1 is a vertical section with parts in elevation through one form of drying reel embodying features of the invention; Figure 2 is an end elevation thereof, parts being shown 45 as broken away; and Figure 3 is a section on line 3—3 of Figure 1. Figure 4 is a section with parts in elevation through a different drying reel embodying features of the invention; Figure 5 is an end elevation thereof; and Figure 6 is a 50 partial section of the distributing means by which

a heating medium may be supplied to the reel of Figures 4 and 5.

A reel embodying features of the invention is illustrated in Figures 1 to 3. The reel therein shown comprises two generally cylindrical members 9 and 10. Member 9, which may be termed the "concentric member," is mounted concentrically upon and for rotation with hollow drive shaft 11. Its periphery is comprised of a plurality of longitudinally extending bar members 12. Member 10, which may be termed the "eccentric member," is rotatably mounted with its axis slightly offset from and inclined to that of member 9. It has a periphery comprised of a plurality of bar members 13 disposed alternately 15 to bar members 12 of concentric member 9.

Concentric member 9, as illustrated in Figure 3, is of rigid, integral construction, preferably of die-cast aluminum. It comprises a cylindrical body portion 14 on the periphery of which are 20 formed longitudinally extending bar members 12 which, as shown, are separated by slots 15. Body portion 14 of member 9 may be made hollow, as shown, forming in effect a thick walled annular reinforcing member for the bar members 12. Body portion 14 may if desired be provided with an integral hub 16 by means of which the member 9 may be concentrically mounted on drive shaft 11. Member 9 is caused 25 to rotate with drive shaft 11 by any suitable means such as that shown, comprising a slot 19 in hub 16 into which slot projects a driving pin 21 mounted in the drive shaft 11.

In the construction illustrated, eccentric member 10 comprises an annular supporting member 22, shown to better advantage in Figure 1, on which is mounted, as by bolts 23, a cage-like member 24. Cage-like member 24 comprises a plurality of longitudinally disposed bar members 13, the number of which is preferably equal to 30 that of bar members 12 of member 9. The bar members 13 are fixed at one end to an annular supporting ring 25, which serves to support the bar members as well as to reinforce them. A high degree of rigidity can be imparted to these end-supported members by the annular rib 26 fixed to the opposite ends of bar members 13. Member 24, as well as annular supporting member 22, may be and preferably is of die-cast aluminum construction, in which case annular reinforcing rib 35 26, as well as the annular supporting and reinforcing ring 25, may be formed integrally with the bar members 13.

Eccentric member 10 is mounted with its axis in the desired offset and inclined relation to the 40

axis of member 9 by means of an eccentric bushing 29 mounted on the frame 27. Bushing 29 is so formed that it has a suitable inclination of the axis of its external surface with respect to the axis of its internal surface, thus providing the desired inclination of the axes of the two reel members 9 and 10. Supporting member 22 rotates upon a sleeve 28 carried by bushing 29, which sleeve 28 is disposed in the same offset and 10 inclined relation as the external surface of bushing 29.

If desired, there may be provided a suitable lubricating system such as that shown, which comprises a lubricant fitting 31 communicating 15 through channels 32, 33 and 34 with the lubricant grooves 35.

To protect that portion of the reel mechanism at the junction of the generally cylindrical members 9 and 10 and to prevent the escape of 20 lubricant, suitable sealing means may be provided. Since there is relative oscillating movement between the two generally cylindrical members 9 and 10, the sealing member should preferably be 25 flexible. A flexible bellows-like sealing member 39 which may take the form shown in Figure 1 has been found satisfactory. As can be seen from the drawing, the sealing member 39 may be fastened to reel member 10 by being clamped between the cage-like member 24 and annular supporting member 22 of reel member 10, a washer 41 being clamped therewith if desired to equalize the clamping pressure. Sealing member 39 may be fastened to reel member 9 by mounting it on a portion of the hub 16, a sleeve 42 being provided if desired.

Rotation of the drive shaft 11 causes the concentric reel member 9 mounted thereon to rotate therewith, whereupon contact of the bar members 12 of this reel member with the bar members 13 of eccentric reel member 10 causes the latter reel member to rotate at the same speed. The offset and inclined relationship of the two generally cylindrical members 9 and 10 causes the thread to wind on the reel and form spaced helical 45 turns which progress axially along the reel. By suitable construction and rotation of the reel, the thread may be caused to progress from the rear of the reel to the front, or from right to left in Figure 1.

As can be seen from Figures 1 and 3, the drying medium, which may be heated air, is supplied to the interior of the reel through hollow drive shaft 11. Ports 45 in drive shaft 11 communicate with the chamber 46 in the interior of body portion 14. Holes 47 in the walls of body portion 14 communicate with the exterior of the reel and thus permit the processing medium to reach the thread stored on the reel. The holes 47 may be of such number and so positioned, preferably between bar members 12, that they supply processing medium over substantially the entire circumference of the reel and for a substantial length of the reel. It is desirable to make the walls 48 of body portion 14 relatively thick, considerably thicker, in fact, than 65 strength requirements make necessary. The presence of a substantial mass of metal aids in drying the thread, providing a high heat capacity which helps level out temperature differences.

It is desirable, further, to provide an enclosure 70 about the reel to prevent excessive consumption of the drying medium. In Figures 1 and 2 is shown a chamber 50 in which the front wall 51 and part of the top wall 52 are formed integrally. When the chamber is opened, it is a simple matter 75 to start the thread on the reel at the rear thereof

and, after the thread has progressed across the reel, to lead it out at the front of the chamber, as through slot 53. When the chamber is closed, interference of the thread with the top wall 52 of the chamber is prevented by a suitably shaped 5 slot 54 therein, while the slot 53 in the bottom of the chamber may be substantially closed by the extending portion 55 at the bottom of the front portion 51.

The construction of the reel disclosed in Figures 4 and 5 is generally similar to that of the reel in Figures 1 to 3, the principal difference being that the reel of Figures 4 and 5 has a closed heating system through which hot water is circulated. Reel member 64, which corresponds to reel member 9 of Figure 1, is hollow, having a cylindrical body portion with thick, imperforate walls. Reel member 62 resembles and corresponds to eccentric member 10 of Figure 1. In operation, eccentric member 62 rotates in the same manner as before, the bearing surfaces comprising the inner surface of sleeve 69 and the outer surface of sleeve 60.

Reel member 62 embodies longitudinally extending bar members 63; similarly, reel member 64 embodies bar members 66. Bar members 66 upon the exterior of reel member 64 are flared in transverse cross section, as shown, so that they are considerably wider at their outer surfaces than elsewhere. Due to their flared formation, the periphery of each bar member 66 nearly bridges the space between the peripheries of the bar members 63, thus presenting a broad thread-bearing surface. The fact that the thread has an increased length of contact with the outer surfaces of bar members 66 makes it possible to dry the thread with a smaller consumption of heating medium than if the bar members were of rectangular cross section.

Hollow shaft 61, upon which reel member 64 is concentrically mounted, communicates with chamber 65 through openings 68. Extending lengthwise along the interior of shaft 67 and spaced concentrically therefrom by sleeve 71 is a conduit 70. Openings 72 provide communication between conduit 70 and chamber 65. It is desirable that openings 72 and 68 open into opposite ends of chamber 65, so that a flow of fluid throughout the length of the chamber will result. The direction of flow is preferably from conduit 70, through openings 72, into chamber 65, through openings 68 and thence out through the hollow shaft 67.

Since the shaft 67 and conduit 70 both rotate, means must be provided to establish communication between each of them and the exterior pipes without interfering with the rotation of the shafts. For this purpose they extend into a coupling block 73 mounted upon the frame of the apparatus. Coupling block 73 is divided into two interior chambers 74 and 75 by a partition 76. Chamber 74 preferably is in communication with a hot water supply pipe 77 and chamber 75 is connected to a pipe 78 for the discharge of the cold water. Shaft 67, which communicates with the chamber 75, is sealed by the packing gland 79 against leakage from the coupling block 73. Conduit 70 is sealed by packing gland 80 against leakage past the partition 76.

It is apparent from the drawings and foregoing description that reels of the forms herein described lend themselves readily to the use of cast constructions. If, as preferred, the reel members are die-cast, the concentric reel member and the cage-like member forming part of the eccentric

reel member may be readily cast in a two-part die of suitable design, the draft of the parts of the die being in the direction of the axes of said members; while the casing of the annular supporting member forming part of the eccentric reel member presents no difficulties in either case. Elements so die-cast require very little, if any, finishing before final assembly, since they can be cast to a high degree of accuracy and smoothness. In addition, the casting of the reel members results in lower costs for the reels in cases where large numbers of reels are to be made, great uniformity as to size, shape, and manner of operation; and a high degree of rigidity, as well as other advantages.

While two reels have been described both of which are adapted to use in connection with the processing or artificial silk thread, such reels are not necessarily restricted to such employment, but find a wide variety of uses in other fields. Various modifications in the reels shown, and various other reels embodying the invention, may be devised without departing from the spirit of the invention. In the appended claims, the term "thread or the like" is intended to include, besides thread, filaments, tapes, bands, tubes and similar articles which may be wound on reels of this type. It is intended that the patent shall cover, by suitable expression in the appended claims, whatever features of patentable novelty reside in the invention.

What is claimed is:

1. In combination with means supplying a heating medium thereto, a unitary thread-advancing reel for drying thread or the like comprising a first reel member embodying a plurality of longitudinally extending bar members, a second reel member embodying a plurality of longitudinally extending bar members flared to present relatively broad thread-bearing surfaces, and means mounting said reel members for rotation in displaced relation with the bar members of one reel member interdigitating with those of the other, one of said reel members having walls of high heat conductivity and, formed within said walls, a cavity for the reception of said heating medium.

2. In combination with means supplying a heating medium thereto, a unitary thread-advancing reel for drying thread or the like comprising a first reel member embodying a plurality of longitudinally extending bar members, a second reel member embodying a plurality of longitudinally extending bar members flared to present relatively broad thread-bearing surfaces, and means mounting said reel members for rotation in offset and inclined relation with the bar members of one reel member interdigitating with those of the other, one of said reel members having walls of high heat conductivity and, formed within said walls, a cavity for the reception of said heating medium.

3. In combination with means supplying a heating medium thereto, a unitary thread-advancing reel for drying thread or the like comprising a first reel member embodying a plurality of longitudinally extending bar members, a second reel member embodying a plurality of longitudinally extending bar members, and means mounting said reel members for rotation in displaced relation with the bar members of one reel member interdigitating with those of the other, one of said reel members being of massive construction, having walls thickened considerably beyond the requirements of strength to provide a high heat storage capacity, and having a cavity formed within said walls for the reception of said heating medium.

4. In combination with means supplying a heating medium thereto, a unitary thread-advancing reel for drying thread or the like comprising a first reel member embodying a plurality of longitudinally extending bar members, a second reel member embodying a plurality of longitudinally extending bar members, and means mounting said reel members for rotation in offset and inclined relation with the bar members of one reel member interdigitating with those of the other, one of said reel members being of massive construction, having walls thickened considerably beyond the requirements of strength to provide a high heat storage capacity, and having a cavity formed within said walls for the reception of said heating medium.

5. In combination with means for supplying heat from an external source of energy, a unitary thread-advancing reel for drying thread or the like comprising two interdigitating reel members mounted for rotation in displaced relation each of which embodies a plurality of spaced, longitudinally extending bar members and one of which embodies a hollow body of high heat capacity to the interior of which heat is supplied from said external source of energy, the bar members of the latter reel member being solid in cross-section, rigidly mounted on said hollow body, and flared to present relatively broad thread-bearing surface.

6. In combination with means for supplying heat from an external source of energy, a unitary thread-advancing reel for drying thread or the like comprising two interdigitating reel members mounted for rotation in offset and inclined relation each of which embodies a plurality of spaced, longitudinally extending bar members and one of which embodies a hollow body of high heat capacity to the interior of which heat is supplied from said external source of energy, the bar members of the latter reel member being solid in cross-section, rigidly mounted on said hollow body, and flared to present relatively broad thread-bearing surfaces.

LAVERN J. JORDAN.
